UNITED STATES PATENT OFFICE.

AUGUST HILDT, OF NEW YORK, N. Y., ASSIGNOR TO L. DRYFOOS & CO., OF SAME PLACE.

DESIGN FOR A QUILTED FABRIC.

SPECIFICATION forming part of Design No. 17,093, dated February 8, 1887.

Application filed November 17, 1886. Serial No. 219,214. Term of patent 7 years.

To all whom it may concern:

Be it known that I, AUGUST HILDT, of the city, county, and State of New York, have invented a new and original Design for Quilting, 5 of which the following is a specification, reference being had to the accompanying drawing, which represents a portion of a strip of fabric quilted in accordance with my invention.

10 The design consists of alternate rows of V-shaped figures *a* and of lines *b*, which connect the extremities of the legs of said figures *a* with the extremities of the corresponding adjoining legs of the next row or rows of V-shaped figures *a*. In the V figures of each row 15 their corresponding legs are parallel with one another, and the figures themselves present the appearance of being "nested" together, the apex of one entering the space included 20 between the legs of the next. The lines *b* of

each row are parallel with one another, and stand at right angles to a line drawn through the apexes of the V figures *a* of the adjoining row or rows.

What I claim, and desire to secure by Letters 25 Patent, is—

The design for quilted fabric, consisting of a series of single rows of nested V-shaped figures, *a*, alternating with rows of parallel lines *b*, which extend between the contiguous legs 30 of the V-shaped figures *a* of adjoining rows, there being one row of lines *b* between each two single rows of figures *a*, as described, and illustrated in the accompanying drawing.

In testimony whereof I have hereunto set 35 my hand this 9th day of November, 1886.

AUGUST HILDT.
